F. L. RE QUA

CHECKING MECHANISM

Filed June 24, 1922

INVENTOR.
Frederick L. Re Qua
BY *Franklin Hubbard*
ATTORNEY.

UNITED STATES PATENT OFFICE.

FREDERICK L. RE QUA, OF WAUKEGAN, ILLINOIS, ASSIGNOR TO THE CUTLER-HAMMER MFG. CO., OF MILWAUKEE, WISCONSIN, A CORPORATION OF WISCONSIN.

CHECKING MECHANISM.

Application filed June 24, 1922. Serial No. 570,759.

To all whom it may concern:

Be it known that I, FREDERICK L. RE QUA, a citizen of the United States, residing at Waukegan, in the county of Lake and State 5 of Illinois, have invented new and useful Improvements in Checking Mechanisms, of which the following is a full, clear, concise, and exact description, reference being had to the accompanying drawing, forming a 10 part of this specification.

This invention relates to checking mechanisms and while not limited thereto is particularly applicable to checking mechanisms for electric controllers.

15 The invention has among its objects to provide an improved mechanism which is positive in action and consists of a relatively small number of parts of simple, rugged and inexpensive construction.

20 Another object is to provide a checking mechanism of the aforesaid character which permits unretarded movement of the controlled device between given positions.

Another object is to provide an improved 25 checking mechanism capable of use in connection with controllers wherein the spacing between the operative positions is not uniform.

Various other objects and advantages of 30 the invention will hereinafter appear.

The accompanying drawing illustrates an embodiment of the invention which will now be described, it being understood that the embodiment illustrated is susceptible of 35 modification without departing from the scope of the appended claims.

In the drawing,

Figure 1 is a front elevational view of a 40 checking mechanism embodying the invention; and

Fig. 2 is a side elevational view of said mechanism.

Referring to the drawing the same illustrates a foot pedal 1 fixed to a shaft 2, and 45 a drum 3 operatively connected to said shaft through the medium of a bevel pinion 5 and a bevel gear segment 6. The checking mechanism includes a lever 7 fixed to shaft 2, an arm 8 pivotally connected to the lower 50 end of said lever and having a pin 9 mounted on the free end thereof, and a fixed labyrinth member 10 to co-operate with said pin.

More specifically arm 8 is yieldingly held

in a given angular relation with respect to 55 lever 7 by a spring 11 having its free ends arranged on opposite sides of lugs 12 and 13 the former lug being associated with lever 7 and the latter with arm 8. Pin 9 is freely rotatable within arm 8, the same being supported by a ball bearing 15 mounted within an opening in said arm and held between plates 16 fixed to opposite sides of the latter. Labyrinth member 10 has a channel 17 60 therein for receiving pin 9, and said channel has a plurality of vanes 18 located therewithin each of which is adapted to move said pin downwardly from its normal position during movement of foot pedal 1 in a clockwise direction and upwardly from such position during movement of said pedal in an opposite direction. The lower wall of channel 17 is formed to provide a series 65 of curved stop surfaces 19, one of said surfaces being located to the left of each of the vanes 18. The left hand wall of channel 17 is formed to provide a stop surface 20 while the upper wall thereof is arranged concentric to the axis of shaft 2 and is spaced from vanes 18 to permit passage of pin 9 between 70 the same and said vanes.

From the foregoing it is apparent that during movement of foot pedal 1 in a clockwise direction vanes 18 will act successively to cause pin 9 to move downwardly and around the lower ends thereof and it is apparent that said pin in passing around the lower ends of said vanes engages the stop surfaces 19 to the left thereof to check the operation of pedal 1. It should be noted 75 that the checking action of stop surfaces 19 is dependent upon the angle between the same and arm 8 and in the embodiment shown the angle is such as to require a slight return movement of pedal 1 to provide for 80 release of pin 9 from said stop surfaces under the action of spring 11. Movement of foot pedal 1 in a clockwise direction is limited by engagement of pin 9 with stop surface 20. During return of foot pedal 1 85 to normal position from any of its intermediate positions or its extreme position pin 9 rides upwardly over the left hand faces of vanes 18 against the action of spring 11 and said pedal can thus be returned to 90 normal position without checking thereof.

In the embodiment shown the several control parts are carried by casing member 25

having a sheet metal cover 26 associated therewith. The upper wall of casing member 25 is provided with a bearing for the left hand end of shaft 2 while the rear wall 5 of said casing is provided with a bearing for the right hand end thereof. Labyrinth member 10 is provided with outwardly projecting lugs 27 for securing to the rear wall of casing member 25 and the shaft of 10 drum 3 is supported in suitable bearing brackets 28 on said wall, one of said brackets being shown. Foot pedal 1 is biased toward the position shown by a spring 29 having its upper end secured to a projecting arm 30 15 on lever 7 and having its lower end fixed to a pin 31 on the rear wall of casing 25. To limit movement of foot pedal 1 under the action of said spring, lever 7 is provided with a projecting tail piece 32 to engage a 20 fixed stop 33 on the upper wall of casing 25.

In the embodiment shown labyrinth member 10 is designed to check foot pedal 1 in positions which are substantially equally spaced but it is apparent that the spacing 25 of stop surfaces 19 can be varied to suit the positions of the controller. Also it is apparent that if desired stop surfaces can be provided in the upper wall of channel 17 to check foot pedal 1 during return thereof 30 to normal position.

What I claim is new and desire to secure by Letters Patent is:

1. The combination with an operating member, of means for checking said member in given positions, said means including a part movable with said member, said part being biased toward an intermediate position, and being movable in opposite directions out of such position, a series of vanes 35 in the path of said part to move the same in opposite directions from said normal position upon movement of said member in reverse directions and a stop associated with each of said vanes and located to one side 40 thereof for engaging said part during movement thereof in one direction between said vanes.

2. The combination with an operating member of means for checking said member in given positions, said means including a series of stops, a part for engaging said 45 stops in given positions of said member, a

pivoted supporting arm for said part movable with said member, said arm being biased toward an intermediate position and being movable in opposite directions out of such position and a series of vanes in the path of said part for moving the latter into engagement with said stops upon movement of said operating member in a given direction. 55

3. The combination with a pivoted operating member, of means for checking said member in given positions, said means including a pivoted arm movable with said member and located at a point removed from the axis thereof, a pin carried by said arm, a series of vanes in the path of said pin to move the same in a plane parallel to the plane of movement of said operating member in opposite directions from a given normal position upon movement of said member in reverse directions and a series of stops adapted to coact with said pin during movement thereof in a given direction between said vanes. 70

4. The combination with a pivoted operating member of checking means therefor including a series of vanes arranged substantially concentric to the axis of said member, a series of stops arranged at one side of said vanes and a pivoted arm carried by said member, said arm being biased toward an intermediate position and being movable in opposite directions out of such position upon reverse movements of said member and a part carried by said arm to be moved by said vanes into engagement with said stops. 80

5. The combination with an operating member of means for checking said member in given positions, said means including a labyrinth member having a series of vanes and stops located at one side of said vanes and a part movable with said operating member, said part being biased toward an intermediate position and being adapted upon movement of said member in one direction to be deflected into engagement with said stops and upon movement of said member in an opposite direction to ride over said vanes. 85

In witness whereof, I have hereunto subscribed my name.

FREDERICK L. RE QUA.
